UNITED STATES PATENT OFFICE.

WILLIAM L. GOMORY, OF CHICAGO, ILLINOIS, ASSIGNOR TO CLIFFORD M. LEONARD,
OF CHICAGO, ILLINOIS.

PROCESS FOR CRACKING HYDROCARBONS.

Application filed February 14, 1920. Serial No. 358,755.

My invention has for its object to provide a continuous process for cracking oil in which a large percentage of the lighter hydrocarbons is obtained with a minimum 5 development of carbon and fixed gases and in which the longevity of the apparatus is increased and the consumption of fuel reduced to a minimum. With these and other objects in view, I continuously force a stream of oil or hydrocarbons through a coil heated to a cracking temperature, injecting with the oil a suitable gas which has the effect of causing what carbon is developed to assume a porous friable state in which it 10 is readily driven out of the heating coil; the gas further assists in driving the carbon out of the coil; preferably I employ a gas rich in hydrogen for the purpose, which further acts to reduce the amount of carbon formed 15 by combining with a portion thereof to form hydrocarbons. In my process moreover, the free carbon is at once eliminated, thus increasing the effectiveness of the apparatus and minimizing the consumption of heat. 20 Other advantages of my invention will appear from the following specification in which I have described a preferred form of apparatus and process; it is to be understood, however, that the specific disclosure is 25 for the purpose of exemplification only and that the scope of the invention is defined in the following claims in which I have endeavored to distinguish it from the prior art so far as known to me without however 30 relinquishing or abandoning any portion or feature thereof.

In the drawing accompanying and forming a part of this application I have shown diagrammatically partly in section and partly 35 in elevation an apparatus for carrying out my invention. The construction comprises a furnace 1 which may be of any suitable or approved type, through the heating chamber of which extends a coil of pipe 2 for heating petroleum or other heavy hydrocarbons to be cracked. Oil is supplied to the coil from a suitable tank or reservoir through a pipe 3 and is forced through pipe 4 by pump 3^a and through to pipe 5 and 40 into the upper end of coil 2. A check-valve 7 in pipe 5 serves to prevent the return of the oil. The oil in the coil of pipe 2 is maintained at a temperature of approximately 1000° Fahrenheit and the oil therein 45 is maintained at a pressure which may be in the neighborhood of 150 pounds, the temperature and pressure being such that 15 to 20 per cent of the oil forced through the coil remains in the liquid phase. In order to assist in the elimination of carbon, as above 50 stated, I introduce with the oil a gas, which causes the carbon formed to be in a light, porous condition and which assists in carrying the carbon out of the heating coil, thus greatly increasing the longevity of the apparatus 55 overcoming one of the greatest difficulties encountered in cracking processes. For this purpose a branch pipe 8 is connected through union 10, check-valve 11 and pipe 9 with a source of steam under pressure. Other inert gas may be employed instead of the steam. Preferably, however, I introduce a gas which is rich in available hydrogen, such as hydrogen gas per se, producer gas or the like. The hydrogen-containing 60 gases have the advantage heretofore described in connection with the introduction of neutral gases such as steam, together with the further advantage that they combine with the carbon to produce hydrocarbons and in this way serve still further to promote the elimination of the carbon from the heating coil. Obviously, however, the hydrogen-containing gases may be introduced without steam. A branch pipe 12 65 having a valve 13 is connected to the union 10 for the introduction of such hydrogen-containing gases.

It will be observed that the oil and gas are introduced at the upper end of the coil 70 2 and as the evolved gases tend to escape upward through the in-coming current of oil the uncondensable gases are largely re-absorbed in the oil. From the lower end of the heating coil the mixture of liquid oil, 75 carbon, vapor and fixed gases is conveyed by pipes 6, 14 to the expansion tank 15 in which there is gravity separation, the heavy hydrocarbon containing the free carbon sinking to the bottom of the tank and the 80 uncondensed vapors and gases rising to the top thereof. A gauge 16 indicates the pressure. From the bottom of the tank the heavy hydrocarbons containing free carbon are drawn off by pipe 17 into a cooler 18 from 85 which they are conducted to a tank or other storage receptacle by pipe 19. Thus the carbon developed in the heating coil is at once removed from the system, and presents 90 no obstacle to the further cracking opera- 95 100 105 110

tion. The uncondensed portions of the mixture rise through pipe 20 and the heavier portions thereof are condensed in tank 21 and return by pipes 22, 4, and 5 to the heating coil. As this oil contains practically no free carbon, its return to the heating coil is unobjectionable. The fixed gases and the vapors remaining uncondensed in tank 21 pass over by pipe 21^a to a condensing coil 23 in which the vapors are condensed. From coil 23 the condensed vapors and fixed gases pass through the receiving tank 24 from which the liquid may be drawn off through valve 25. The receiving tank is provided 15 with a pressure gauge 26 and a pressure valve 27, the latter being for the purpose of releasing or carrying away the fixed gases as the pressure rises above the desired point.

The process has been described in connection with the description of the apparatus, but may be briefly stated as follows: Pressure is maintained throughout the system from the inlet of the heating coil to the receiving tank, slightly diminishing from the former to the latter but a sufficient pressure being maintained in the latter to maintain any desired pressure of say approximately 150 pounds in the heating coil. The temperature of the oil in the heating coil is raised to about 1000° Fahrenheit, the precise temperature and pressure being determined by the fact that about 15 to 20 per cent of the oil is to be maintained in the liquid phase. The heat within the coil results in the splitting up of the heavier hydrocarbons into lighter hydrocarbons with the deposition of carbon, the latter being deposited in porous, friable form because of the introduction of gas for that purpose, and when the gas introduced contains a supply of hydrogen a certain part of the carbon is eliminated by combination with hydrogen. At the same time that cracking takes place a considerable volume of non-condensable gas is developed which tends to rise upward in the coil but is thereby brought into contact with, and absorbed by the in-coming stream of oil. The mixed products of the heat treatment are carried over into the expansion tank 15 where they are separated by gravity, the heavier portions containing the fixed carbon settling to the bottom and being drawn off through the cooling tank and then to storage. The portions or components which do not condense in the tank 15 rise through the pipe 20 into tank 21 where the heavier portions thereof are condensed and returned by

pipes 22 and 4 to be re-treated, it being noted that this component contains practically no free carbon and therefore introduces no new difficulty into the treatment. The lighter vapors and fixed gases pass outward through pipe 21^a to condenser 23 where the vapors are condensed and flow with the gases into receiving tank 24, where the liquid is separated from the fixed gas. By separating the free carbon and heavy hydrocarbon and returning only fractions of the oil practically free from the carbon, the life of the coil is increased since practically no carbon is re-introduced thereinto and, furthermore, the consumption of heat is correspondingly reduced.

I claim:

1. A process of cracking hydrocarbons 75 consisting in forcing a mixture thereof with hydrogen through a conduit heated to a cracking temperature, maintaining a pressure in said conduit such that about fifteen to twenty per cent of the hydrocarbons remain in the liquid phase at the temperature employed, drawing off the resulting liquid, vapors and gases, separating the liquid and condensing the vapors.

2. The process of cracking hydrocarbons 85 consisting in forcing a mixture of the hydrocarbons and hydrogen through a conduit, heating the mixture therein to a temperature of approximately 1000 degrees F., maintaining a pressure in the conduit of approximately 150 pounds and thereby vaporizing between 80% and 85% of the mixture, drawing off the resultant liquid, vapors and gases, separating the liquid and condensing the vapors.

3. A process of cracking hydrocarbons which consists in continuously passing a stream thereof downwardly through a heating conduit maintained at a temperature of approximately 1000 degrees F. and then into a tank, maintaining a body of the liquid products from the cracking conduit quiescent in said tank, condensing the heavier portion of the vapors escaping from said tank and mixing the condensate with the stream of oil flowing to the cracking conduit, separately condensing the lighter portion of the vapors and maintaining a pressure on the cracking conduit, tank and condensers sufficient to retain between 15% and 20% of the oil in the cracking conduit in the liquid phase.

WILLIAM L. GOMORY.
